ELECTRIC INDICATING APPARATUS

Karl Torsten Källe, Säffle, Sweden

Application May 6, 1948, Serial No. 25,427
In Sweden October 24, 1945

2 Claims. (Cl. 177—351)

1

The present invention refers to an improvement of an arrangement for the remote indication of steam pressure, temperature, of a type known from a previous patent to the same inventor (Swedish Patent No. 67,175). The known arrangement operates in such a manner that the magnitude to be measured, through some suitable means, is allowed to act upon one of the contacts in a contact device whose other contact is actuated by a heating wire. The current which the contact device switches off and on in dependence of the magnitude to be measured and of the temperature of the heating wire flows through the heating wire and is transmitted to the distant indicating device. The effective value of the current pulses thus produced constitutes the measure of the magnitude to be measured.

Owing to the fact that the heating wire must have the required physical strength and consequently a fixed minimum area, its electrical resistance will be small so that the current intensity will have to be relatively great in order to obtain the required rapid heating of the heating wire. If, as in arrangements hitherto known, the contact device is included in the same circuit as the heating wire, the contact has then to interrupt this entire current intensity which readily gives rise to arcs so that the contacts become burned. Furthermore, because of the low resistance of the heating wire, only a low voltage can be applied to the circuit. This involves the drawback that variations in contact resistance due to burns or the like affect the current intensity to a high degree.

In accordance with the present invention, therefore, an arrangement is proposed, wherein the contact device in series with the source of current is connected in circuit with the primary winding (high tension winding) of a transformer and wherein the heating wire is connected in the measuring circuit in series with the secondary winding (low tension winding) of the transformer.

Also, a form of execution is proposed, wherein in the primary of the transformer is provided with a center tap and wherein the contact device in series with the source of current is connected to one of the halves of the primary, whose second half in series with a condenser for extinguishing the arc between the contacts at the breaking operation is in parallel with the breaking point of the contact device and with the series connection of said first half of the primary and the source of current.

The advantage with the arrangement accord-

2

ing to the invention is that the secondary of the transformer supplies the required heavy current but a low voltage, while the primary in series with the contact device may be connected to the A. C. mains, that is to a relatively high voltage so that the current intensity becomes less for the same effect as in the secondary.

With the present arrangement it is possible to maintain the voltage high and the current intensity low in the contact circuit and simultaneously therewith to obtain a current of the proper intensity through the heating wire.

In the figure of the accompanying drawing there is shown by way of example an embodiment of the invention. One of the conductors 1 from an A. C. source of current is connected to one of the halves 9 of the primary winding 9, 10, 12 and the other conductor 7 is connected to one of the contacts 3 of the contact device. The center tap of the primary is connected with the other contact 4 of the contact device through the conductor 8. The second half 10 of the primary in series with a condenser 11 is disposed in parallel to the contacts 3, 4. The contact 3 is actuated by a Bourdon tube 2 communicating with a boiler (not shown) or the like, the steam pressure of which is to be measured, and the contact 4 is carried in a support 14 by means of a spring 5. A heating wire 6 is clamped in the support 14 and is kept stretched by the spring 5. The wire 6 is included in a circuit, fed by the transformer 9, 10, 12 and comprising: the secondary 12, a conductor 15, the spring 5, the wire 6, a conductor 16, the primary of a transformer 13 and a conductor 17. The secondary of the transformer 13 feeds an indicating instrument comprising two metal springs 18 and 19, an electrically conducting bridge 20 joining the springs 18, 19, a hand 21 and a scale 22. When the same current flows through the springs 18 and 19, they become heated but dilate differently so that when clamped as shown they function as a bimetal. The curvature of the springs and hence the position of the hand 21 constitutes the measure of the effective value of the current flowing through the springs.

In order to explain the operation of the arrangement it is assumed that a certain pressure exists in the Bourdon tube 2 so that it has straightened itself to a certain degree and that the contacts 3, 4 are closed for the moment so that the transformer winding 9 is connected to the A. C. source. In the transformer winding 55 there is produced a current which flows through

the heating wire 6 and in so doing heats said wire. Owing to the thermal expansion thereof and the action of the spring 5 the contact 4 is brought downwards causing a breaking of the contact engagement. The condenser 11 in series with the transformer winding 10 prevents the formation of possible arcs between the contacts. When the primary current in the transformer is interrupted, its secondary current ceases too, in consequence of which the wire 6 is no longer energized and begins to cool down and contract. When the wire 6 has resumed its original length, the contacts 3 and 4 are remade and the same process will be continually repeated as long as the pressure in the tube 2 remains constant. The alternating current pulses produced by the breaking and closing of the contacts pass through the transformer 13 and the springs 18 and 19, which are heated by the current and then, as stated above, bend so that the position of the hand 21 corresponds to the effective value of the current. At a uniform pressure in the tube 2 the periods of closed contacts are obviously of the same length of time and also the periods of open contacts. The effective value of the current pulses and hence the position of the hand 21 thus becomes constant at a constant pressure. If the pressure increases, the tube 2 will have time to straighten itself a little, while the contacts are open, and therefore the contacts 3 and 4 will be remade before the wire has resumed its former length. At the same time, as the minimum temperature of the wire 6 must be higher in order that its new minimum length will correspond to the new position of the contact 3, the heat emission from the wire to the surroundings becomes greater owing to higher temperature of the wire. Consequently, the periods of closed current become longer and the intervals between them become shorter at the state of equilibrium for the new pressure. Thus, the effective value of the current and hence the deviation of the hand 21 becomes greater.

Other embodiments of the invention are possible within the scope of the claims. Thus, the arc may be extinguished by means of a resistor and a condenser respectively in series and in parallel with the contacts.

What I claim is:

1. An electric indicating apparatus comprising a current source and conductors leading therefrom, a transformer having a primary and a secondary winding, said secondary winding comprising the low tension winding of said trans-

former, one said conductor being connected to the primary winding of said transformer, a contact device, said contact device including a pair of contacts, a member dependent on the magnitude to be measured carrying one said contact, said contact carried by said member being connected to a second said conductor from said source, a spring carrying the second of said contacts, said second contact being connected to the primary winding of said transformer, a thermo-responsive heating wire connected to the secondary winding of said transformer and to said spring carrying said second contact, a measuring element connected in series with said heating wire and said secondary winding, the position of one of said contacts being dependent on the magnitude to be measured and the position of the other contact carried by said spring being dependent on the variations in length of the heating wire for controlling the opening and closing of the contact device, the measure of the magnitude to be measured being the effective value of the current pulses produced by the opening and closing operations of the contact device fed to the heating wire.

2. In an electric indicating apparatus as claimed in claim 1, a center tap connecting the said contact device in series with the source of current to one-half of the primary of said transformer, a condenser connected in series with the second half of said primary winding and in parallel to the breaking point of said contact device and the series connection of said first half of said primary winding and said source of current.
